FOOT DEODORANT PAD

Joseph J. Lynch, Upper Montclair, and Richard Semke and Harold J. Wombley, Jersey City, N. J., assignors to Foot Filter, Inc., Jersey City, N. J., a corporation of New Jersey

Application November 16, 1935, Serial No. 50,090

11 Claims. (Cl. 36—44)

This invention relates to a foot deodorant pad and this application is in part a continuation of our co-pending application Serial No. 14,552, filed April 4, 1935.

5 Persons troubled with perspiring feet under normal every day conditions and in spite of their efforts for personal hygiene, find it embarrassing due to odors caused thereby. It is therefore one of the principal objects of this invention to provide a pad for insertion into the shoe of a wearer which does not interfere with the natural sweating of the foot but absorbs perspiration therefrom and deodorizes the same to arrest any obnoxious odors which ordinarily would emanate 10 therefrom.

Another feature of the invention resides in an antiseptic foot deodorizer which includes a foot pad constructed of gossamer-like layers of cellulose material containing a deodorant substance 15 having sublime characteristics so as to be effective only when the body heat and perspiration from the foot of a user renders the same chemically active to change the normal solid state of the substance into a state of vapor. Thus the 20 strength of the deodorant is ever present in the pad until use of the same and loss of the strength is avoided during intervals between use, for such sublime substances as we employ for deodorant purposes condense or return to their original or 25 normal solid state in the absence of heat.

A further feature of the invention is to provide in the pad body compressed portions which impart, first, strength to the pad structure; secondly, it fixes the medication to insure its permanent, even distribution and prevents sifting of the same; and thirdly, it eliminates buckling or shifting of the delicate foils or gossamer like 30 layers.

Another feature of the invention is the provision of an antiseptic deodorant foot pad which 40 will not injure or irritate the foot of a user nor cause undue wear upon the stocking or sock, and will not impair the shape of the shoe.

45 A further feature of the invention resides in a hygienic deodorant foot pad which is absorbent and which in the presence of body heat and perspiration releases the deodorant, aromatic, and antiseptic vapors within the shoe of a user, and about the foot therein.

50 A still further object of the invention is the provision of a deodorant foot pad having the above features which is simple and inexpensive of manufacture to enable retail sale at a price 55 which will enable complete disposal of the article

after limited use without undue expense to the users thereof.

With these and other objects in view, the invention resides in certain novel construction, combination and arrangement of parts, the essential features of which are hereinafter fully described, are particularly pointed out in the appended claims, and are illustrated in the accompanying drawing, in which:

Figure 1 is a perspective view of the deodorant 10 foot pad in its finished condition.

Figure 2 is an enlarged vertical transverse sectional view on the line 2—2 of Figure 1.

Figure 3 is an enlarged detail vertical sectional view on the line 3—3 of Figure 1. 15

Figure 4 is a collective plan view of the deodorant pad and its tubular fabric covering in separated relation.

Figure 5 is a perspective view showing the tubular fabric covering which may or may not be 20 treated with rubber, in position over the deodorant pad body prior to the final cutting and stitching operation.

Figure 6 is a collective perspective view of the 25 pad stiffening base and pad in separated condition, a portion of the layers of the pad being turned up to illustrate the deodorant in position.

Figure 7 is an enlarged vertical transverse sectional view on the line 7—7 of Figure 6 through one of the compressed areas. 30

Figure 8 is an enlarged detail vertical sectional view through one end of a modified construction of deodorant foot pad.

Figure 9 is a top plan view of a further modified form of the invention. 35

Figure 10 is a top plan view of a still further modification of the invention.

Referring to the drawing by reference characters, the numeral 10 designates our deodorant foot pad in its entirety which comprises broadly, 40 a flexible base 11, a soft porous absorbent pad body 12 impregnated with a deodorant, antiseptic, and aromatic substance, and a fabric covering 13. The base 11 is of a shape corresponding to that of the sole of a shoe, into which the 45 article is adapted to be inserted for use, the edges of the pad body 12 following the curvatures of the base 11. It will be understood that the articles will be constructed in "right" and "left" to be sold in pairs, and they will also be made in 50 different sizes to fit into different sized shoes.

The base 11 may be constructed of any suitable thin flexible material such as cardboard sized on the underside, although any equivalent thereof may be employed if desired. 55

The pad body 12 is composed of creped or uncreped sheeted cellulose wadding. This wadding is constructed of a plurality of gossamer thin sheets, plies, layers, foils, laminae, or the like 14, 5 of pulped cellulose fibers. These pulped cellulose fibers are obtained from disintegrated wood, rags, grass, or other vegetable matter. The nucleated and connective fibers of each gossamer thin sheet are so arranged as to create a close, 10 consistent, tenuous feltwork, web-like construction or felted sheet of homogeneous fibers that are highly absorbent.

The blank of cellulose wadding from which the pad 12 is die cut, is treated with a deodorant 15 sublime substance by inserting such substance between certain of the gossamer like sheets 14. Such deodorant substance may either be sprayed onto the layers 14 or if the substance is of a solid powdered form, the same may be sprinkled 20 between the layers as shown in Figure 6 of the drawing. Whereas various medicaments may be employed as the sublime deodorant, we have found that excellent results occur by the use 25 of paraformaldehyde or trioxymethylene for the reason that this chemical not only deodorizes the perspiration but prevents and destroys rancidity and decomposes the deposits of fat, salt, urea, etc., which are present in sweat and which cause the obnoxious odors. When paraformaldehyde 30 is subjected to heat, and in this instance, to body heat, it sublimes, that is it forms a vapor which on cooling returns to solid state, thereby insuring a minimum loss of medicament when the pad is not in use. Thus, when the pad is not in use 35 the paraformaldehyde does not receive the body heat and therefore there can be no sublimation, and with no sublimation vapor cannot escape.

If desired, the use of menthol may be resorted to because of its universally recognized cooling 40 and soothing effect on the skin surface.

In connection with the above mentioned substances, boric acid is used as a reducing agent to regulate the strength of the paraformaldehyde and menthol, aside from which, in itself, possesses decided and proven antiseptic properties 45 and is used in deodorizing fetid sweating.

The pad 12 is cut by a die and during the cutting operation, the die compresses the marginal edges of the layers 14 so as to produce a substantially beveled unitary edge upon the pad and imparts thereto the appearance of a single layer 50 of material. These compressed edges are designated by the numeral 15 and serve to seal the layers of gossamer like sheets entirely around the marginal edge. This sealing of the edges creates of the pad in its entirety a completely housed depository for the sublime deodorant substance 55 16.

Prior to the die cutting of the pad, portions 60 of the pad are compressed from opposite sides as at 17, these compressed portions extending at spaced intervals along the length and breadth of the pad. The compressed portions 17 serve to bind the compressed layers of material together to prevent shifting of the layers in manufacture and during use by the wearer. The compressed portions also strengthen the structure 65 of the pad 12 and fix the medicament to insure its permanent substantially even distribution and 70 lessen its sifting through the layers of material and over the edges of the pad body.

As a practical matter, the compressed portions, or indentations 17 may be formed by passing a series of superposed sheets wherein the medicament is housed through suitable rollers having a

knurled, fluted or other suitable structure, which will serve to compress or indent the sheets as desired.

The outer covering 13 constitutes a single length of flat tubular knitted fabric, which may 5 or may not be treated with rubber, of a normal width less than the minimum width portion of the pad 12 as illustrated in Figure 4 of the drawing. The material from which this covering is constructed is loosely knitted to provide sufficient 10 elasticity to permit distension of the same when the pad 12 and its base 11 are inserted into the covering through one end thereof whereby the covering will contract and closely adhere to the opposite sides and marginal edges of the pad 15 and base. After insertion of the pad 12 and the base 11, the ends 23 and 24 of the elastic fabric that extend beyond the heel and toe are drawn taut in opposite directions, whether or not treated 20 with rubber. This operation causes the fabric covering to snugly conform to the opposite sides and marginal edges of the pad and base. Figure 25 5 of the drawing illustrates the pad and base after its insertion into the covering 13 and after such insertion the outer covering, while still taut, is stitched to the ends of the pad and base as at 18. After stitching the covering, pad and base, at the heel and toe, the outer extending ends 20 and 24 of the length of material are cut away, 30 it being appreciated that the length of the outer covering must be at least equal to the length of the pad.

After the covering has been applied to the pad and base in the manner just described, these parts are secured together by overedge stitching 35 19 which extends entirely around the marginal edge of the article.

In practice, the deodorant foot pads are sold in pairs and inserted into the shoes of a wearer, and in addition to the main purpose of deodorizing 40 the odors of the feet, the pads serve as a soft insole which will diminish the tenderness of the feet. Any perspiration of the feet will be absorbed by the antiseptic absorbent pad 12 of the deodorizer unit and due to the body heat imparted thereto together with the perspiration will effect a chemical action in the sublime deodorant causing vapors to be released from the pad, it being understood that both the body of the pad and the covering are of porous substances. Thus, 45 50 objectionable odors, known as bromidosis, will be deodorized by the deodorant, aromatic and antiseptic vapors emanating from the pad.

In Figure 8 of the drawing, a slightly modified form is shown wherein the ends of the article are 55 dipped in latex after the pad 12 and the base 11 are inserted into the tubular covering 13. The latex seal is designated by the numeral 20 and is employed in lieu of the stitchings 18 and 19 hereinbefore described. The marginal edge 60 stitching may be dispensed with in this type of construction.

In Figure 9 of the drawing, a further modified construction 12' of pad 12 is shown, the same being constructed of layers of gossamer like cellulose 65 material, the layers being secured together by cross stitching or quilting 21, which creates of the pad in its entirety a completely housed depository for the sublime deodorant substance 16; strengthens the pad structure; fixes the medicament to insure its permanent substantially even 70 distribution and lessens its sifting between the layers of gossamer-like material.

In Figure 10 of the drawing, a still further modified form is shown wherein stitching 22 ex- 75

tends about the marginal edge of the pad 12" to secure the layers of gossamer like cellulose material together in lieu of the compressed edges 15 shown in the preferred embodiment.

5 Although we have shown and described the ends of the covering 13 as being stitched as at 18 and as being secured by latex at 20, other modifications may be resorted to if desired, such as basting at the heel and toe, and over edge stitching 10 at the heel and toe only.

While we have shown and described what we consider to be the most practical embodiments of our invention, we wish it to be understood that any changes as come within the scope of the 15 appended claims may be resorted to if desired.

Having thus described the invention, what we claim as new and desire to secure by Letters Patent of the United States, is:—

1. A foot deodorizer comprising in combination, 20 a soft flexible pad of shoe sole shape composed of a plurality of sheets of gossamer like cellulose material arranged one upon the other, a sublime deodorant substance distributed between certain of said sheets, quilted portions 25 formed at spaced distances over the area of said pad to aid in maintaining the distribution of the deodorant substance, and an outer protective covering enclosing said pad.

2. A foot deodorizer comprising in combination, 30 a flexible base of shoe sole shape, a plurality of gossamer-like layers of cellulose material positioned against one side of said base to form a pad and being of a shape conforming to that of said base, a sublime deodorant substance interposed between certain of said layers of material, 35 a tubular mesh fabric covering snugly enclosing the pad and base, and stitching securing the edges of the pad, and base, and the fabric covering together.

40 3. A foot deodorizer comprising in combination, a soft flexible porous absorbent pad of shoe sole shape containing a sublime deodorant substance, and a tubular covering of elastic mesh material snugly fitting about said pad and conforming to the shape thereof, the ends of said tubular covering being adhesively secured to said pad.

4. A foot deodorizer comprising in combination, 50 a soft flexible pad of shoe sole shape composed of a plurality of plies of gossamer-like cellulose material, a sublime deodorant substance equally distributed between certain of said plies of material, portions of said plies of material being bound together at spaced distances over the area thereof to aid in maintaining the equal distribution 55 of the deodorant substance, and an outer porous protective covering snugly enclosing said pad.

5. An article of manufacture comprising a plurality of superposed gossamer-like layers of cellulose material forming a laminated pad body, and a sublime deodorant substance between certain of the layers of gossamer-like cellulose material, the perimeter of said layers of material being compressed into a substantially unitary edge.

65 6. A foot deodorizer comprising in combination, a soft flexible laminated pad of shoe sole shape composed of a plurality of like plies of gossamer-like cellulose material, the perimeter of said plies of gossamer-like cellulose material being compressed into a substantially unitary edge, a de-

odorant substance interposed between certain of the plies of material, portions of the plies of material being compressed at spaced distances throughout the area thereof to bind the same together, and an outer porous protective covering 5 surrounding said pad.

7. A foot deodorizer comprising in combination, a flat flexible base of a shape to fit within a shoe, a soft porous absorbent laminated pad positioned against the top side of said base and conforming to the marginal shape thereof, said laminated pad being composed of a plurality of plies of gossamer-like absorbent material, a normally sublime deodorant substance interposed between certain of the plies of material and being chemically responsive to the body heat and perspiration of the foot of a user to effect vaporization of the sublime deodorant substance, and a porous covering enclosing said base and pad. 10

8. A foot deodorizer comprising in combination, 20 a soft flexible porous absorbent pad of shoe sole shape composed of a plurality of superposed layers of gossamer-like cellulose material, a sublime deodorant substance interposed between certain 25 of the layers of cellulose material, a flexible base of a shape corresponding to that of said pad and disposed therebeneath, an open-mesh elastic tubular covering snugly enclosing said pad and base, and stitching securing the edges of the pad and base, and the tubular covering together. 30

9. A foot cushion for insertion into a shoe comprising a pad of shoe sole shape composed of a plurality of plies of delicate cellulose material, a flexible base of a shape corresponding to and underlying said pad, and an elastic distended 35 fabric protective covering having inherent contracting characteristics enclosing said pad and base and securing the plies of material of said pad against relative movement when the foot cushion is in use within the shoe of a wearer. 40

10. The method of making a deodorant foot pad which consists in interposing a powdered sublime deodorant substance evenly between certain of the plies of a blank of gossamer-like cellulose material, cutting a pad from the blank of cellulose material of a shape and size to fit within a shoe, compressing the perimeter of the plies of gossamer-like cellulose material to form a unitary edge about said pad, and snugly enclosing the cut pad in a porous fabric protective covering. 50

11. The method of making a deodorant foot pad which consists in interposing a powdered sublime deodorant substance evenly between certain of the plies of a blank of gossamer-like cellulose material, cutting a pad from the blank of cellulose material of a shape and size to fit within a shoe, compressing the perimeter of the plies of gossamer-like cellulose material to form a unitary edge about said pad, superimposing the pad upon a flexible base, inserting the pad and base as a 60 unit into a length of tubular elastic porous covering material whose normal width is less than the width of said pad and base to cause said elastic porous covering material to snugly fit about said pad and base, and finally securing said 65 pad, base, and covering material together.
